UNITED STATES PATENT OFFICE.

CLAYTON TRIDLE ULREY, OF EAST ORANGE, NEW JERSEY, ASSIGNOR TO WESTINGHOUSE LAMP COMPANY, A CORPORATION OF PENNSYLVANIA.

X-RAY TUBE ADAPTED FOR HIGH VOLTAGE.

Application filed September 4, 1925. Serial No. 54,446.

This invention relates to X-ray tubes and more particularly to a high voltage X-ray tube in which no severe electrical stresses are impressed upon the glass walls of the envelope thereof.

High voltage X-ray tubes of usual design embody a large spherical bulbous portion and two oppositely extending arms of substantially equal length, which support the electrodes of the tube. Tubes of this nature frequently puncture because of the severe electrical stresses upon the glass walls of the tube, especially at a point near the juncture of the cathode arm with the bulbous portion of the envelope. The reason for the high electrical stresses at this portion of the tube is that on the outside of the tube there is a leakage current from one electrode terminal to the other, thus causing a drop in potential over the glass surface approximately proportional to the distance from either terminal. If the voltage drop across the electrodes is assumed to be 250,000 volts, then it is obvious that the potential difference between the glass and the metal of either electrode, assuming the potential of the electrodes to be the same throughout their lengths, will vary in proportion to the distance along the surface of the bulb when moving from one terminal to the other. If the distance of the juncture point of either arm with the spherical portion of the envelope is one-third of the total distance along the surface of the envelope between the electrode terminals, then the voltage at such point would be one-third of 250,000 volts or about 83,000 volts. Owing to the close spacing of the electrode shank from the glass walls at this point as well as the small radii of curvature of the arm, this electrical stress upon the glass may prove too great for the glass to withstand the same with the result that puncturing occurs.

According to my invention, I reduce the length of the cathode arm to such an extent as to cause a reduction in the potential impressed upon the glass at the point where it joins the spherical portion of the envelope so that danger of puncturing is reduced.

Therefore, it is an object of my invention to so design the envelope of an X-ray tube as to prevent puncturing of the glass walls

thereof at points adjacent the juncture of the electrode arms and the spherical portion of the envelope.

A more specific object of my invention is to provide an X-ray tube with a relatively short cathode arm and a relatively long anode arm whereby the electrical stresses upon the envelope where the electrode stems are spaced closely therefrom are reduced to a minimum.

Other objects of my invention will be apparent from reading the following detailed description.

Referring to the drawing, for a better understanding of the invention, the single figure illustrates a longitudinal sectional view of an X-ray tube embodying the invention.

An X-ray tube embodying my invention may comprise a main spherical bulb or chamber 2 having outwardly and oppositely extending arms 3 and 4. The arm 3 which may be termed the cathode arm, is adapted to house the leading-in wires 5 and 6 which are connected to a cathode 7 of the thermionic type. A focusing cup 8 of usual design is provided to uniformly distribute the electrons coming from the cathode 7 over the face of the large disk target 9. A central projection 11 extending outwardly beyond the edge of the focussing cup and positioned centrally thereof and connected to one of the cathode leads assists in dispersing the electron stream so that the electrons uniformly strike the face of the target. The purpose of this construction is to effectively dissipate the heat generated in the large disk target through electronic impact.

The target 9 is supported by a stem 12 which in turn is suitably secured to a sleeve 13 mounted upon a reentrant glass tube 14 sealed to the anode arm 4.

Especial attention is directed to the comparative lengths of the cathode arm 3 and the anode arm 4, the former being relatively short as compared with the latter. The advantage of this construction will be appreciated more fully from the following explanation and furthermore constitutes the important feature of the present invention. Preferably the arm 3 is about one-eighth of the total overall length of the tube. However, the relative proportions of the arm may be

varied as well as the overall length of the tube depending entirely upon the operating voltage applied to the tube.

In order to more fully understand the invention, a brief description will first be given as to the construction of the usual form of high voltage X-ray tube, particularly with reference to the structural details thereof which are the cause of such tubes frequently puncturing. Tubes of the usual design have their cathode and anode arms of substantially equal length. Viewing the figure shown in the drawing and considering the arm 4 to be approximately half the length therein shown, and the cathode arm 3 of substantially equal length thereto, an X-ray tube of usual design is then obtained in so far as the envelope construction is concerned. Suppose it be assumed that the distance from the end of the anode arm to the end of the cathode arm is thirty inches and the length of the arms are ten inches and that an operating potential of 250,000 volts is impressed across the electrodes. Furthermore, that the potential drop over the glass surface between the ends of the electrode arms is substantially uniform and that the potential drop along the length of the electrodes from the electrodes proper to the ends of the arms is negligible, then the potential difference between the cathode and the glass of the tube at the point of intersection of either arm with the spherical portion of the glass envelope is about 80,000 volts. If it is assumed that the cross section of the necks are relatively small say 1 to 2 inches in diameter, and this is usually the case, then puncture may very easily occur at the juncture points of the arms with the bulbous portion of the envelope because of the nearness of the electrodes or their stem or leads thereto and the relatively small radii of curvature of the glass at such points.

For the purpose of comparison, let it be assumed that the overall longitudinal dimension of the tube in the drawing is 30 inches, that is, the same as the tube in the example given in the preceding paragraph, and that the diameter of the main bulb is the same in each instance. Now instead of making the cathode arm 10 inches in length as in the previous illustration, assume that it is very short, say 3 inches. Obviously then, the potential stress at the intersection of the cathode arm with the spherical arm will be considerably less than that in the usual tube, since with an impressed potential of 250,000 volts, the electric stress will be 3-30 of 250,000 volts or 250,000 volts, which stress is considerably less than the 80,000 volt stress prevailing in the usual tubes.

It is to be understood that although the electrical stress at the juncture of the anode arm with the spherical bulb may be increased by reason of my construction, I have ob-

served that puncture does not occur at this end of the tube but usually takes place, if at all, at the cathode end. The reason for this is not fully understood but may be attributed to electronic impact upon the glass which 70 may be already in a strained condition by reason of the large electrical stress. Owing to the fact that the electrons moving in the direction of the anode are deflected thereto, it is apparent that there is very little if any 75 electron impacts upon the walls of the tube at the anode end, particularly at the juncture of the anode arm with the spherical portion of the envelope.

The electrical field inside the tube is such 80 as to cause an accumulation of electrons on the inside surface of the glass near the cathode extension of the bulb. This, however, does not produce a dangerous strain on the glass in this region in a tube of my construction since the outside surface also acquires an accumulation of negative electricity by leakage from the cathode terminal.

Although I have described what I now, 90 consider the preferred embodiment of my invention, it is to be understood that the same is merely illustrative and that modifications may occur to those skilled in the art within the spirit and scope of the appended claims.

What is claimed is:

1. An X-ray tube comprising a main spherical bulb portion and a pair of outwardly extending arms, an anode and a thermionic cathode supported by said arms, said cathode supporting arm being materially shorter than the anode supporting arm, and a focussing device surrounding said cathode and insufficient in size to intercept electrons emanating from said anode, whereby puncture of the tube by electrical stresses 100 is diminished.

2. An X-ray tube comprising a main chamber and anode and cathode arms outwardly extending therefrom, an anode and a thermionic cathode partly surrounded by 110 said arms, said cathode arm having a length less than the length of said anode arm and about equal to one-eighth the overall length of said tube, and a focussing cup surrounding said cathode and insufficient in size to prevent electronic bombardment of the walls 115 of the tube adjacent the cathode arm.

3. An X-ray tube comprising a main spherical chamber, an arm projecting therefrom and materially longer than the diameter of said chamber, another arm extending from said chamber and shorter than the diameter of said chamber, an anode and a thermionic cathode supported by said arms, and a focussing device surrounding said 120 cathode and insufficient in size to prevent electronic bombardment of the walls of the tube adjacent said cathode.

4. An X-ray tube comprising an envelope 125 having a spherical chamber and a pair of

- arms extending outwardly from said chamber and in opposite directions, an anode supported by and sealed to one arm and a thermionic cathode supported by and sealed to the other arm, the overall length of said tube being such as to prevent a discharge over the surface of said envelope between the terminals of said anode and cathode, the cathode arm being of such length with respect to the overall length of the envelope that the electrical stress is a minimum at the point where said arm joins the spherical chamber when a maximum potential is applied to said tube, and a focussing device surrounding said cathode and of insufficient size to intercept electrons emanating from said anode.
5. An X-ray tube comprising an envelope having a spherical compartment and outwardly extending and oppositely disposed arms secured to said compartment, an anode and a thermionic cathode within said compartment, electrical conductors connected to said anode and cathode and hermetically sealed within the outer ends of said arms,

said arms being of unequal length, the shorter of said arms being of such length with respect to the overall length of the tube as to prevent detrimental electrical stress at its juncture with the spherical compartment and a focussing device surrounding said cathode and insufficient in size to prevent electronic bombardment of the walls of the tube adjacent the cathode.

6. An X-ray tube comprising a bulb, a cathode and anode mounted in said bulb, means for heating said cathode and means associated with said cathode for dispensing the electron stream emanating from the cathode so that the electrons uniformly strike the face of the target, said target consisting of a relatively thin disk of large size and so proportioned as to effectively radiate the heat generated therein through electronic impact without requiring external cooling means.

In testimony whereof, I have hereunto subscribed my name this 3rd day of September, 1925.

CLAYTON TRIDLE ULREY.
